UNITED STATES PATENT OFFICE.

HENRY W. WINTER, OF METHUEN, MASSACHUSETTS, ASSIGNOR TO UNITED SHOE MACHINERY COMPANY, OF PATERSON, NEW JERSEY, A CORPORATION OF NEW JERSEY.

GRINDING OR POLISHING MACHINE.

1,115,640.

Specification of Letters Patent.

Patented Nov. 3, 1914.

Application filed May 3, 1909. Serial No. 493,667.

To all whom it may concern:

Be it known that I, HENRY W. WINTER, a citizen of the United States, residing at Methuen, in the county of Essex and State 5 of Massachusetts, have invented certain Improvements in Grinding or Polishing Machines, of which the following description, in connection with the accompanying drawings, is a specification, like reference 10 characters on the drawings indicating like parts in the several figures.

This invention relates to machines in which an operating member or members are mounted upon a shaft and has particular 15 reference to means whereby said member or members may be readily replaced. This class includes a great variety of machines of which those used for grinding and polishing will serve as examples.

20 The invention is illustrated in connection with a finishing machine commonly known as a "finishing shaft" used in the manufacture of boots and shoes. It is common to mount upon the shaft of these machines a 25 variety of abrading and polishing devices which may be used as desired. For convenience, however, the invention will be described in connection with a finishing machine which is provided with polishing devices only.

These machines ordinarily comprise a base which carries a plurality of bearings in which a comparatively long shaft rotates. Fixed upon this shaft are a plurality of polishing devices, the nature of which varies 35 according to the result desired. Commonly the shoes are subjected to the action of three classes of operating members, first to the action of a felt covered member known as a 40 blending roll, the function of which is to work the dressing into the leather, second to the action of a polishing brush and third to the action of a polishing roll, the acting portion of which is composed of some soft 45 material, as for instance yarn, and the function of which is to impart to the shoe its final luster. It frequently becomes necessary because of wear or for some other reason to replace one of these operating members. Hitherto it has been common practice 50 partially to dismantle the machine in order to permit the worn member to be slipped off the end of the shaft; and if said member happened to be mounted near the 55 longitudinal center of the shaft it became

necessary to remove all the operating members between the worn one and the end of the shaft. The disadvantages of this procedure are obvious, and considerable effort has been spent in an endeavor to produce 60 a polishing member provided with a split hub, so that said member might be placed on the shaft or removed therefrom without disturbing the remaining members or the shaft. Certain difficulties have however, 65 arisen particularly with respect to the brushes. It has been found that the bristles of a split brush tend to become compact at that point in the working surface where the two sections of the brush come together and 70 to wear away at each side of said point, a result which is obviously most undesirable.

One object of this invention, therefore, relates to a sectional shaft having provision whereby an operating member may be 75 placed thereon or removed therefrom, at a point intermediate its ends. Or, since the sections may be considered if desired as separate shafts, this object may be said to be attained by providing a plurality of aligned 80 shafts separably connected. Any convenient means for accomplishing this may be employed, and in the illustrated embodiments of the invention two forms are shown, one in which the sections (or the aligned shafts) 85 are held together by a pin and another in which the joint between the sections (or aligned shafts) is incased in a member which serves to hold said sections (or shafts) in line with each other, while separate means 90 are provided for preventing relative longitudinal movement.

For convenience the sections will be referred to in the remaining part of the description as forming together one sectional shaft, but it should be understood 95 that this is done merely to promote brevity.

In order that the placing of an operating member upon the shaft and its removal therefrom may be facilitated it is desirable 100 that the adjacent ends of the sections of the shaft be capable of transverse movement with respect to each other; and a further object of this invention relates to the provision of means whereby such a movement 105 is permitted. This may conveniently be accomplished by providing the adjacent ends of the sections with a sliding connection which compels rotation in unison when properly confined but permits transverse 110

movement when the confining member is partially or wholly removed. In the illustrated embodiment this result is accomplished by so mounting the bearings that they are capable of angular movement, it then being possible after freeing the joint from its confining member, to swing one or both sections of the shaft angularly and thereby break said shaft at a point intermediate its ends.

It is often desirable to cover a machine of this class with a hood particularly when there has been mounted upon the shaft an abrasive member the operation of which produces dust. Inasmuch as the hood may interfere with any extended angular movement of the sections of the shaft in one direction it is desirable that means may be provided whereby the ends of the sections of the shaft may be swung free from the hood; and another object of this invention relates to the provision of such means. In the illustrated embodiment this is accomplished by mounting the bearings in such a manner that they are capable of angular movement in two directions. With this construction and arrangement the sections of the shaft may be moved angularly in one direction to separate their ends and then said ends may be swung out from beneath the hood into a position in which the greater part of said sections are readily accessible.

Another object of this invention relates to means for reciprocating the shaft while it is being rotated, since it has been found that this combined movement tends to produce better results. This is accomplished in the illustrated embodiment by a plurality of grooved collars fast to the sections of the shaft and a plurality of coöperating fingers mounted in brackets which are fixed to the bearing boxes. In this way the collars and fingers serve the double purpose of preventing relative longitudinal movement between the sections of the shaft and of reciprocating said sections in unison.

Another object of this invention relates to automatic means for lubricating the bearings.

These and other features of the invention including certain details of construction and combinations of parts will be explained in connection with the following description of a machine and will be pointed out more definitely in the claims.

Referring now to the accompanying drawings.—Figure 1 is an elevation of a finishing machine embodying one form of this invention, a portion of one standard being broken away; Fig. 2 is a perspective partly in section of the bearing which confines the ends of the sections of the shaft, the cap of said bearing having been removed; Fig. 3 is an elevation of a finishing machine embodying a second form of this invention;

and Fig. 4 is a perspective showing the abutting ends of the sections of the shaft with the pin removed.

Referring first to Figs. 1 and 2 a base 1 carries a plurality of standards 3 having 70 bores 5. In these bores are mounted pins 7 which are held in adjusted position by screw bolts 9. Pivoted to each pin 7 by means of a screw 11 is a yoke 13 through the ends of the arms of which screws 15 75 pass, the forward ends of said screws engaging sockets 17 in the bearing boxes 19. With the construction thus far set forth it is evident that the bearing boxes may be adjusted into horizontal alignment and held in position by means of the screw bolts 9, while angular movement in two directions is at the same time possible. In order to limit the abutting ends of the sections 37, 39 of the shaft against transverse movement it is 80 desirable to provide a confining member, and in the illustrated embodiment said member is shown as a bearing box in every way like the end boxes with the exception that it is split longitudinally and the cap 21 is 85 held in place by eyebolts 23 and nuts 25, said bolts being pivoted to brackets 27 by means of pins 29. After the nuts have been loosened the bolts can be swung aside and the cap removed for a purpose presently to 90 be described. In order to insure proper lubrication of the bearings each box is provided with a reservoir covered by a steel plate 33 upon which rests the usual lining 95 of babbitt 35. Through the plate and babbitt, 100 its upper end flush with the surface of said babbitt, extends a wooden plug 36 the function of which is to convey oil from the reservoir to the rotating shaft. Mounted in the bearings described above are the sections 37, 105 39 of a rotary shaft, and in order to cause the sections to rotate in unison said sections are provided with interengaging ends which are formed in the illustrated embodiment as a tongue and groove connection. In order to 110 prevent relative longitudinal movement of these sections a plurality of grooved collars 41 are fixed to said shaft, the grooves being engaged by fingers 43 which in turn are mounted in brackets 45 fixed to the bearing 115 boxes 19 by means of screws 47. To cause reciprocation of the rotary shaft any convenient means may be provided, and in the illustrated embodiment the grooves 49 in the collars have a corresponding curved formation so that upon rotation of the shaft the sections are reciprocated in unison. Although in the illustrated embodiment these collars which hold the shaft in place are modified so as to produce reciprocation it 120 should be understood that an entirely independent means may be provided if desired. It has been found that the polishing roll which is used to add the final luster produces better results if rotated at less speed 125 130

than are the brushes and other rolls. Accordingly the polishing roll 51 is shown as fast to a pulley 53 which is rotatable on the section 37 of the shaft and is held from longitudinal movement by collars 55 and 57, a belt 59 being provided to transmit power to said pulley and roll. Fast to the other section of the shaft there is shown a brush 61. It should be noticed, however, that the sections of the shaft are broken in several places and it should be understood that operating members of various kinds may be mounted upon said sections both between the end bearings and outside of them. It should also be understood that the number of sections or of separably connected shafts is not limited and that any convenient number may be used if desired. In order to rotate the shaft there is mounted upon one of the sections a fast pulley 63 having a tubular extension 65 upon which latter is mounted a loose pulley 67, said loose pulley being held in place by a collar 69 fastened to the extension and shaft by a pin 71. This loose pulley has driven tightly into its bore a bushing 73 having an annular groove which cooperates with the wall of said bore to form a reservoir 75 for lubricant, a plurality of wooden plugs 77 similar to the plugs 36 being driven through holes in the bushing and extending into the reservoir. In operation power is applied to the pulley 63 and the shaft thereby rotated, simultaneous reciprocation being produced by the action of the collars 41 and the fingers 43. When it is desired to remove from the shaft one of the operating members the belt is thrown off, the cap 21 is removed and the abutting ends of the sections lifted thereby causing them to separate. If the machine is fitted with a hood the ends of the sections may then be swung outward about the pivot screws 11. The desired changes may now be made in the operating members after which the angular movements of the shaft may be reversed, the cap replaced and power applied.

Referring to Figs. 3 and 4 there is shown another embodiment of the invention. The base, the standards and the yokes are identical with those shown in Figs. 1 and 2 except that the pins 71 are integral with the yokes 131. Neither the boxes 191 nor the loose pulley 691 are provided with oil reservoirs but otherwise they are similar to the corresponding elements shown in Figs. 1 and 2. The collars 411 are fastened to the shaft by means of screws 79 but are not provided with grooves since in this form the shaft is not reciprocated. The sections 371 and 391 are connected by means of the joint shown in Fig. 4. A stud 81 at the end of the section 371 fits into a socket 83 formed in the end of the other section 391, and a tongue 85 engages a groove 87, while a taper pin 89

is driven through alining holes 91 in the walls of the groove and in the tongue respectively. There is shown mounted upon the sections of this shaft a brush 611 and a blending roll 93 but it should be understood that these shafts are of comparatively great length and that a plurality of operating devices are commonly mounted upon each section. With the machine shown in Figs. 3 and 4 separation of the sections is effected by driving out the pin and pulling the sections apart.

As has been stated, in order to insure clearness and to avoid prolixity the shaft has been referred to as a sectional one, but it is clear that the sections thereof may be considered with equal accuracy as a plurality of separably connected shafts. And although the invention has been shown and described in connection with a finishing machine it should be understood that nothing herein contained is to be construed as limiting the invention in the scope of its application to the particular machine shown and described.

The invention having been thus described, what is claimed and desired to be secured by Letters Patent is:—

1. A grinding or polishing machine having, in combination, a plurality of alined shafts having abutting ends which are separably connected, a plurality of vertically adjustable bearings for said shafts, an operating member mounted upon one of said shafts between said abutting ends and one of the adjustable bearings, means whereby said bearings may be moved angularly in two directions to separate the ends of said shafts, and means for rotating one of said shafts.

2. A grinding or polishing machine having in combination, a plurality of separably connected alined shafts, an operating member fast to one shaft, a second operating member loose upon the other shaft, means for rotating one of said shafts and independent means for rotating said loosely mounted operating member.

3. A grinding or polishing machine having, in combination, two alined shafts separably connected, a bearing for each of said shafts, said bearings being angularly movable, to permit separation of the adjacent ends of said shafts, an intermediate bearing to receive the connected ends of said shafts, and an operating member mounted upon one of said shafts between the bearing for said shaft and the intermediate bearing.

4. A grinding or polishing machine having, in combination, two alined shafts having a tongue and groove connection, a bearing for each shaft angularly movable to permit separation of the ends of said shafts, a split bearing to receive the connected ends of said shafts, said split bearing comprising

- a readily removable cap, and an operating member mounted upon one of said shafts between the split bearing and the bearing for the shaft.
5. A grinding or polishing machine having, in combination, a sectional shaft, the abutting ends of the sections being provided with a tongue and groove connection to compel them to rotate in unison, means for rotating said sections, and separate means acting upon each section constructed and arranged to cause said sections to be reciprocated in unison.
6. A grinding or polishing machine having, in combination, a plurality of bearings,
- a sectional shaft mounted therein and having abutting ends, and an operating member mounted upon said shaft between one of the bearings and the abutting ends of the sections, one of said bearings being angularly movable to permit separation of the abutting ends of said sections for removal and replacement of said operating member.

In testimony whereof I have signed my name to this specification in the presence of 25 two subscribing witnesses.

HENRY W. WINTER.
